UNITED STATES PATENT OFFICE.

JOE BENTON TURMAN, OF WILLOWS, CALIFORNIA.

ALFALFA AND RICE LAND CHECKER.

1,200,054.

Specification of Letters Patent.

Patented Oct. 3, 1916.

Application filed December 21, 1915. Serial No. 67,985.

To all whom it may concern:

Be it known that I, JOE BENTON TURMAN, a citizen of the United States, residing at Willows, in the county of Glenn, State of California, have invented certain new and useful Improvements in Alfalfa and Rice Land Checkers; and I do declare the following to be a full, clear, and exact description of the same, reference being had to the accompanying drawings, and to the characters of reference marked thereon, which form a part of this application.

This invention relates to improvements in graders and scrapers used for throwing up of check levees for preparation of land for irrigation especially in connection with alfalfa and rice lands, the object of the invention being to produce a double bladed scraper or grader having its blades converging toward each other at one end whereby the land may be scraped and thrown up into the levee grade in a rapid and efficient manner. Also the blades are capable of being raised and lowered for the purpose of controlling the amount of land handled by the same at any given time and also for the purpose of transporting the device from one point to another.

A further object of the invention is to produce a means whereby when the scraping blades are lowered for action, additional weight may be forced against them for the purpose of making the blades work deeper into the soil or ground.

A still further object of the invention is to produce a simple and inexpensive device and yet one which will be exceedingly effective for the purposes for which it is designed.

These objects I accomplish by means of such structure and relative arrangement of the parts as will fully appear by a perusal of the following specification and claims.

In the drawings, similar characters of reference indicate corresponding parts in the several views.

Figure 1 is a top plan view of the complete device. Fig. 2 is a front elevation of the same. Fig. 3 is a sectional view of a blade and its hanger. Fig. 4 is a fragmentary view showing the elevating and lowering mechanism.

Referring now more particularly to the characters of reference on the drawings, the

invention consists primarily of a supporting structure comprising a main front beam 1 having side beams 2 converging together at their rear end to form a substantial triangular supporting frame.

Suitably journaled at the converging point of the beams 2 is a pilot supporting wheel 3 and on each end of the front beam 1 is a supporting wheel 4, the supporting wheels 4 having spindles 5 projecting in a turnable manner through the beam 1, and each being provided at its upper end with a projecting arm 6.

The numeral 7 designates a link connecting the arms 6. A steering rod 8 connects one of the arms 6 with the draw bar 9 which is suitably connected to the supporting frame in any desired manner. When the draw bar 9 is moved in one direction or the other it operates the steering rod 8 to pull the arms 6 in such direction, which, through the medium of the spindles 5, will turn the wheels 4 likewise in the desired direction.

The machine may be drawn forward by connecting the motive power with the draw bar 9 which may be either an engine of any desired type, or suitable animals for the purpose.

Paralleling the triangular frame and spaced a slight distance from each side thereof, is a scraper blade 10. These blades are shaped very similar to the common form of molding board used on plows and are edged along the lower sides with metal, or if desired, the blades themselves may be made entirely of metal. These blades are connected with the supporting frame by means of the following structure, namely:

Hinged along the sides of the triangular supporting frame, as at 11, are supporting hangers 12 which over-arch the blades 10 and are fastened to the same, as at 13, each blade having brace bars 14 projecting upwardly therefrom and connected with the hangers 12, as at 15. From approximately the center of each of the blades 10 I connect a draw chain 16 which connects with the forward ends of the triangular shaped supporting frame, as at 17, so that with the forward motion of the supporting frame the blades 10 will be pulled forward with the said triangular frame.

The raising and lowering of the blades 10, and the forcing of the same into the ground

for scraping and leveling purposes is accomplished by means of the following structure, viz: A supporting beam 18 projects substantially central of the triangular supporting frame, and is provided with two upwardly projecting supporting posts 19 and 20 journaled in which is a roller or shaft 21. On one end of the shaft 21 is a pinion 22 which intermeshes with another pinion 23 5 on a shaft 24 journaled on the post 20 and provided with an operating crank 25. On the shaft 24 is a ratchet wheel 26 engageable by a dog 27 mounted on the post 20 whereby the shaft 24 may be held against rotation 10 when desired.

Secured to the shaft 21 are two cables 27 which project outwardly and connect with one of the hangers 12 on each of the blades 10. With the operation of the crank 25 the 15 shaft 24 is rotated causing the pinion 23 to drive the pinion 22 and rotate the shaft 21 to wind the cables 27 on said shaft 21, which will raise or lower the blades 10 as may be desired.

25 A cable 28 is secured to the shaft or roller 21 in the reverse direction to the cables 27 and extends downwardly under a pulley 29 thence under a pulley 30, thence up to a triangular plate 31. A link 32 connects each 30 side of the plate 31 with the hanger 12 on each of the blades 10. When the shaft 21 is rotated to unwind the cables 27 and allow the blades 10 to drop against the ground, this action simultaneously winds the cable 35 28 upon the said shaft 21. This action pulls the plate 31 downwardly and forces the links 32 against the hangers 12 and forces the blades 10 to cut deeper into the ground by reason of this action tending to throw the 40 weight of the supporting frame against the said blades.

From the foregoing description it can readily be seen that with the forward motion of the device the dual blades 10, converging as they do toward each other at their rear ends, will scrape the dirt and distribute it at the rear end into a grade either for levees or other desired formations. Also 45 from the foregoing description it can readily be seen that I have produced such a device as substantially fulfills the objects of the invention as set forth herein.

While this specification sets forth in detail the present and preferred construction of the device, still in practice such deviations 55 from such detail may be resorted to as do not form a departure from the spirit of the invention, as defined by the appended claims.

60 Having thus described my invention what I claim as new and useful and desire to secure by Letters Patent is:

1. A device of the character described comprising the combination with a supporting frame, of a pair of scraper blades

hinged to the supporting frame and converging toward each other at their rear ends, chains connected with the forward end of the frame and midway between the scraper blades, and means carried by the frame for raising and lowering the scraper blades, as described.

2. A device of the character described comprising the combination with a substantially triangular supporting frame, a pair of scraper blades extending substantially parallel with two sides of the frame at a spaced distance therefrom, rigid hangers hinged to the frame and arching over and being hinged to the outer sides of the scraper blades, and means carried by the frame for raising and lowering the blades, as described.

3. A device of the character described comprising a supporting frame, rigid hangers hinged to the supporting frame, scraper blades hinged to the outer ends of said hangers, a shaft turnable on the supporting frame, and cables connected with the hangers and arranged to be wound around the shaft to raise the scraper blades, as described.

4. A device of the character described comprising a supporting frame, rigid hangers hinged to the frame, scraper blades hinged to the outer ends of said hangers, a plate normally disposed above the plane of the hangers, links connected with the plate and with the hangers, a pulley disposed in a lower plane than the plate, and a cable connected with the plate and extending under the pulley and arranged to be operated to draw the plate downwardly to force the scraper blades downwardly, as described.

5. A device of the character described comprising a supporting frame, blades hinged to the supporting frame, a rotating shaft on the frame, and means for rotating same, cables on the shaft connected with the blades for raising and lowering the same with the rotation of the shaft, another cable on the shaft arranged in a reverse position thereon to the first named cables, a plate having links connected with the blades, such last named cable extending under pulleys on the frame and being connected with such blade to draw the same downwardly when such last named cable is wound upon the shaft, as described.

6. A device of the character described comprising a supporting frame, rigid hangers hinged to the frame, scraper blades hinged to the outer ends of said hangers, a plate normally disposed above the plane of the hangers, links connected with the plate and with the hangers, a pulley disposed in a lower plane than the plate, a cable connected with the plate and extending under the pulley and arranged to be operated to draw the plate downwardly to force the scraper blades

blades downwardly, and a shaft carried by the frame and arranged for operating said cable, as described.

7. A device of the character described comprising a supporting frame, scraper blades, rigid hangers hinged to the supporting frame and arching over and hinged

to the outer sides of the scraper blades, and chains connected centrally of the blades and to the supporting frame, as described.

In testimony whereof I affix my signature.

JOE BENTON TURMAN.
